US00D774493S

(12) **United States Design Patent** (10) **Patent No.:** **US D774,493 S**
(45) **Date of Patent:** **** Dec. 20, 2016**

(54) **REMOTE CONTROL**

- (71) Applicant: **SKY UK LIMITED**, Isleworth, Middlesex (GB)
- (72) Inventors: **Andrew Wong**, Herrenberg (DE); **Christopher Kuh**, San Francisco, CA (US)
- (73) Assignee: **SKY UK LIMITED**, Isleworth, Middlesex (GB)

(**) Term: **15 Years**

(21) Appl. No.: **29/564,954**

(22) Filed: **May 17, 2016**

Related U.S. Application Data

- (62) Division of application No. 29/521,038, filed on Mar. 19, 2015.

(57) **CLAIM**

The ornamental design for a remote control, as shown and described.

DESCRIPTION

FIG. 1 shows a perspective view of a remote control showing a new design;

FIG. 2 shows a front elevation view thereof;

FIG. 3 shows a rear elevation view thereof;

FIG. 4 shows a right side elevation view thereof;

FIG. 5 shows a left side elevation view thereof;

FIG. 6 shows a top plan view thereof; and,

FIG. 7 shows a bottom plan view thereof.

1 Claim, 7 Drawing Sheets
